US0D1105730S

(12) **United States Design Patent** (10) **Patent No.:** **US D1,105,730 S**
(45) **Date of Patent:** **** Dec. 16, 2025**

(54) **SHOE**

(71) Applicant: **Bottega Veneta S.R.L.**, Montebello Vicentino (IT)

(72) Inventor: **Matthieu Blazy**, Milan (IT)

(73) Assignee: **BOTTEGA VENETA S.R.L.**,
Montebello Vicentino (IT)

(**) Term: **15 Years**

(21) Appl. No.: **29/958,569**

(22) Filed: **Aug. 20, 2024**

(30) **Foreign Application Priority Data**

Feb. 24, 2024 (EM) 015051720-0001

(57) **CLAIM**

The ornamental design for a shoe as shown and described.

DESCRIPTION

FIG. 1 is a perspective view of a shoe showing my new design;
FIG. 2 is a front view thereof;
FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines depict portions of the shoe that form no part of the claimed design.

1 Claim, 7 Drawing Sheets
